US00D951352S

(12) **United States Design Patent** (10) **Patent No.:** **US D951,352 S**
(45) **Date of Patent:** **** May 10, 2022**

(54) **LABEL**

(71) Applicant: **Merck KGaA**, Darmstadt (DE)

(72) Inventors: **Sven Erfurth**, Darmstadt (DE);
Christian Kuechenthal, Darmstadt (DE); **Jeffrey Whitford**, Darmstadt (DE)

(73) Assignee: **Merck KGaA**, Darmstadt (DE)

(**) Term: **15 Years**

(21) Appl. No.: **35/508,479**

(22) Filed: **Nov. 20, 2019**

(80) **Hague Agreement Data**

Int. Filing Date: **Nov. 20, 2019**

Int. Reg. No.: **DM/205358**

Int. Reg. Date: **Nov. 20, 2019**

Int. Reg. Pub. Date: **Jan. 31, 2020**

(51) **LOC (13) Cl.** **19-08**

(52) **U.S. Cl.**

USPC **D20/22**

(58) **Field of Classification Search**
